US00D926469S

(12) **United States Design Patent** (10) **Patent No.:** **US D926,469 S**
Barlier (45) **Date of Patent:** **** Aug. 3, 2021**

- (54) **BAG**
(71) Applicant: **KeepCool USA LLC**, Orinda, CA (US)
(72) Inventor: **Pierre Barlier**, Lafayette, CA (US)
(73) Assignee: **KeepCool USA LLC**, Orinda, CA (US)
(**) Term: **15 Years**
(21) Appl. No.: **29/715,814**
(22) Filed: **Dec. 4, 2019**
(51) LOC (13) Cl. **03-01**
(52) U.S. Cl. **USPC D3/283; D3/246**
(58) **Field of Classification Search**
USPC D3/203.1, 203.6, 202, 205, 215, 217, D3/226, 229, 230, 232, 233, 242-246, D3/249, 258, 273, 274, 276, 283-290, D3/294, 295, 299, 301, 303, 900-904; D7/602, 605, 607, 619.1, 709; D28/73, D28/76
